UNITED STATES PATENT OFFICE.

WAYNE B. NOTTINGHAM, OF PHILADELPHIA, PENNSYLVANIA, ASSIGNOR TO WESTERN ELECTRIC COMPANY, INCORPORATED, OF NEW YORK, N. Y., A CORPORATION OF NEW YORK.

ARRANGEMENT OF CARRIER CHANNELS IN MULTIPLEX SIGNALING SYSTEMS.

Application filed December 24, 1925. Serial No. 77,473.

This invention relates to multiplex carrier signaling systems, and particularly to arrangements of the carrier channels in such systems.

5 An object of the invention is to reduce cross-talk interference between the channels of multiplex carrier signaling systems.

A feature of the invention is a multiplex carrier signaling system in which the necessary amount of attenuation of the high frequency leakage between the paired receiving and transmitting channels is materially reduced.

In accordance with the invention, in a multiplex carrier signaling system in which all of the channels transmitting in one direction employ carrier frequencies below a certain value, and all of the channels transmitting in the opposite direction employ carrier frequencies above this value, the one-way channels utilizing the lower group of frequencies are paired with the one-way channels utilizing the higher group of frequencies to form the opposite sides of two-way channels in such a manner as to make the near end interference between the channels appear as side tone rather than cross-talk.

Side tone may be defined as the measure of the interference between the transmitting and receiving circuits at the same terminal of the same two-way channel, while near end cross-talk as used in this specification may be defined as the interference produced in the receiving circuit of one channel by the transmitting circuits of one or more other channels at the same terminal of the multi-channel system.

The objects and features of the invention will be clear from the following detailed description when read in connection with the accompanying drawing in which the single figure shows a terminal station of a multiplex carrier telephone system embodying the invention and curves illustrating the principles of the invention.

The invention will be described in connection with a three-channel multiplex carrier telephone system of the carrier suppression type, although it is applicable as well to other types of multiplex carrier systems.

In such a system, the carrier wave of each channel is suppressed from transmission when no signals are being sent, and when

signals are being transmitted, modulation components of the modulated wave are sent over the line, but no unmodulated components of the carrier wave are transmitted. In order to reproduce the signal from modulated waves of this character, it is necessary that the carrier wave supplied to the demodulator at the receiving station be of substantially the same frequency as the carrier wave which was suppressed at the transmitting station. A system of this general character is described in connection with Fig. 49 of an article entitled "Carrier current telephony and telegraphy" by Messrs. Colpitts and Blackwell published in the Transactions of the American Institute of Electrical Engineers, volume 40, 1921.

The single figure of the drawing shows the east terminal of a three-channel carrier telephone system of the type described above. As the west terminal (not shown) of the system has terminal apparatus identical with and arranged in the same manner as that at the east station, only the east terminal need be described.

The terminal apparatus shown in Fig. 1 comprises three transmitting channels TC_1 , TC_2 , and TC_3 connected through a common transmitting circuit TL to the multiplex line ML , and three receiving channels RC_1 , RC_2 , and RC_3 connected through a common receiving circuit RL to the multiplex line ML .

The carrier currents utilized for transmission over the line ML are grouped as to their frequencies, the higher frequencies as a group, being used for transmission from west to east and the lower frequencies as a group being used for transmission from east to west.

Included in the common transmission circuit TL connecting the transmitting channels TC_1 , TC_2 , and TC_3 to the multiplex line ML are a transmitting amplifier TA and a low-pass grouping filter LGF , and in the common receiving circuit RL connecting the receiving channels RC_1 , RC_2 , and RC_3 to the multiplex line ML a receiving amplifier RA and a high-pass grouping filter HGF . The filters HGF and LGF serve to separate the directional groups of carrier waves to the respective terminal transmitting and receiving circuits. These filters and each of the other filters shown through-

out the system may be designed in accordance with the principles set forth in the U. S. patent to Campbell 1,277,113, issued May 22, 1917.

- 5 The low frequency lines L_1 , L_2 , and L_3 , which may be telephone lines or other types of signaling lines, are balanced with artificial networks N_1 , N_2 , and N_3 and are associated with the respective transmitting and receiving circuits through the differential repeating coils H_1 , H_2 , and H_3 , commonly known as hybrid coils, which enable independent transmission in the two directions between the lines and high frequency terminal apparatus.

Transmitting channel TC_1 includes a modulator M_1 and a band filter TBF_1 , transmitting channel TC_2 , a modulator M_2 and a band filter TBF_2 , and transmitting channel TC_3 , a modulator M_3 and a band filter TBF_3 . Receiving channel RC_1 includes a demodulator DM_1 and a band filter RBF_1 , receiving channel RC_2 , a demodulator DM_2 and a band filter RBF_2 , and receiving channel RC_3 , a demodulator DM_3 and a band filter RBF_3 .

The modulators M_1 , M_2 , and M_3 are of the balanced type disclosed in the U. S. patent to Carson 1,343,306, June 15, 1920, designed to suppress the unmodulated carrier from transmission. The demodulators DM_1 , DM_2 , and DM_3 may be of the well-known vacuum tube balanced type shown in Fig. 49 of the Colpitts and Blackwell article, *supra*.

Carrier currents of the frequency assigned to channel TC_1 are supplied from a source TO_1 to the modulator M_1 wherein they are modulated by voice frequency currents or other signaling currents from the low frequency line L_1 . Similarly carrier frequencies of the frequency assigned to the transmitting channels TC_2 and TC_3 are supplied from sources TO_2 and TO_3 , respectively to the modulators M_2 and M_3 , wherein they are modulated by signaling currents from the low frequency lines L_2 and L_3 , respectively. Similarly, carrier sources RO_1 , RO_2 , and RO_3 are associated with the demodulators DM_1 , DM_2 , and DM_3 to supply the incoming side bands in each receiving circuit with the carrier current which was suppressed at the other end of the line ML .

The low-pass filters F_1 , F_2 , and F_3 are respectively inserted in the connections between receiving channels RC_1 , RC_2 , and RC_3 , and the particular transmitting channels with which they are paired, and are used to prevent the carrier from the sources RO_1 , RO_2 , and RO_3 from leaking back into the transmitting channels through unbalance in the hybrid coils.

The band filters TBF_1 , TBF_2 , and TBF_3 in transmitting channels TC_1 , TC_2 , and TC_3 , respectively, and the band filters RBF_1 , RBF_2 , and RBF_3 , in the receiving channels

RC_1 , RC_2 , and RC_3 , respectively, are designed so as to transmit one of the side bands, either the upper or lower as desired, produced by modulation in the respective channels and to suppress from transmission frequencies lying outside of such bands.

Voice frequency currents originating, for instance, in the low frequency line L_1 at the east station pass through the associated hybrid coil H_1 into the modulator M_1 and modulate therein carrier current from the oscillator TO_1 . Of the components of modulation appearing in the output circuit of modulator M_1 , the transmitting band filter TBF_1 suppresses all except one side band, for example, the lower side band which it transmits to the common transmission circuit TL . This side band is amplified by the amplifier TA and then is passed by the low-pass grouping filter LGF to the multiplex line ML and thence to the west station.

Similarly, the incoming side band received over the line ML from the west station is passed by the high-pass grouping filter HGF to the receiving circuit RL , amplified by the receiving amplifier RA , and selected by the respective receiving band filters in the receiving channels for transmission to the respective low frequency lines. For example, currents passing through the receiving band filter RBF_1 are combined in the modulator DM_1 with carrier waves from the source RO_1 , and the voice frequency components of demodulation in the output circuit of the modulator DM_1 are passed through the low-pass filter L_1 and through the particular hybrid coil connected thereto to one of the low frequency lines.

In the system as shown in the figure, the low-pass grouping filter LGF and the high-pass grouping filter HGF have such cut-off points as to divide the available carrier range, which in practice is about 3 to 30 kilocycles, into two parts at a frequency of about 15.0 kilocycles. As stated previously it is assumed that the lower part of the frequency range, that is, 3 to 15 kilocycles, is to be utilized for the channels transmitting west and the upper frequency range, 15 to 30 kilocycles, is to be utilized for channels transmitting east. The width of the side bands transmitted by each of the channels is selected from quality considerations as 2500 cycles.

It will be assumed that the carrier frequencies assigned to the transmitting channels TC_1 , TC_2 , and TC_3 at the west station are 14,000, 10,700, and 7,700 cycles, respectively, and to the receiving channels RC_1 , RC_2 , and RC_3 , 16,100, 19,750, and 23,400 cycles, respectively. It will also be assumed that the transmitting band filters in the system are such as to transmit the lower side bands and the receiving band filters such as to transmit the upper side bands. For prac-

tical considerations, in such a system it is advisable to set the carrier frequency in each channel at some point slightly outside the transmitted bands of the band filters. The transmission ranges of the transmitting band filters TBF_1 , TBF_2 , and TBF_3 will accordingly be selected as 11,300-13,800 cycles, 8,000-10,500 cycles and 5,000-7,500 cycles, respectively, and those of the receiving band filters RBF_1 , RBF_2 , and RBF_3 , 16,300-18,800 cycles, 19,950-22,450 cycles, and 23,600-26,100 cycles, respectively.

The free transmission bands of the respective transmitting and receiving band filters, and of the grouping filters of the system and their cut-off points are indicated graphically in the diagram associated with the figure. In this graphical diagram, frequency is plotted as abscissæ and attenuation as ordinates. The particular curves corresponding to the different filters are indicated by characters similar to those used for designating the filters in the system. The direction of transmission and the position of the carriers with reference to the transmission bands of the filters are indicated by the vertical, full-line arrows.

The particular division of the available carrier range described above and illustrated in the figure is one that is being used in present installations of three-channel carrier telephone systems, and has been selected in accordance with practical considerations.

The ranges of the respective band filters in the transmitting and receiving channels of the system having been fixed, the problem is to pair the one-way channels to form the opposite sides of the two-way channels in such a way as to reduce cross-talk interference due to intermodulation between the side band frequencies in the respective channels to a minimum.

This has been accomplished in accordance with the invention by pairing a channel utilizing an intermediate carrier frequency in the lower group with the channel utilizing the lowest carrier frequency in the upper group, and pairing the channel utilizing the highest carrier frequency in the lower group with a channel utilizing an intermediate carrier frequency in the upper group. Accordingly as shown in the figure low frequency line L_1 is associated through hybrid coil H_1 with transmitting channel TC_1 and with receiving channel RC_2 , and low frequency line L_2 is associated through hybrid coil H_2 with transmitting channel TC_2 and with receiving channel RC_1 . The low frequency line L_3 is associated through hybrid coil H_3 with transmitting channel TC_3 and with receiving channel RC_3 . The advantage of such an arrangement will be brought out in the following discussion.

Let it be assumed that the channels TC_1 , TC_2 , and TC_3 , are being simultaneously used

for transmitting messages. Then each side band frequency transmitted by any one of the transmitting band filters may combine in the transmitting amplifier TA with all of the side band frequencies transmitted by the other transmitting band filters to produce modulation products of second, third, and higher orders, which products pass through the grouping filter LGF . Some of these modulation products are of such a level that even with the loss introduced in them within the suppression range of the low-pass grouping filter LGF , they are of the degree of magnitude of the low level currents coming over the line, and consequently are passed through grouping filter HGF in receiving circuit RL with the incoming line currents, amplified by the receiving amplifier RA , and are effective in the individual receiving channels. Of these modulation components, only the third order products need be considered as they are the only troublesome products from the standpoint of cross-talk.

If s_1 , s_2 , and s_3 are side band frequencies passed by the transmitting band filters TBF_1 , TBF_2 , and TBF_3 , respectively, the third order modulation products resulting are:

$$\begin{array}{ccc}
 3s_1 & 3s_2 & 3s_3 \\
 2s_1 + s_2 & 2s_1 + s_3 & 2s_2 + s_3 \\
 2s_2 + s_1 & 2s_3 + s_1 & 2s_3 + s_2 \\
 2s_1 - s_2 & 2s_1 - s_3 & 2s_3 - s_3 \\
 2s_2 - s_1 & 2s_3 - s_1 & 2s_3 - s_2
 \end{array}
 \quad 95$$

The pairing of the transmitting channels with the receiving channels as described above and illustrated in the figure, makes the particular ones of the above third order modulation products which are objectionable appear in the receiving channels as side tone rather than as cross-talk as in the case of other arrangements. This may be shown as follows:

It will be assumed, first, that the carrier channels, instead of being paired in the manner shown in the drawing, are paired, as in the usual manner, symmetrically with respect to the frequency spectrum, between the two groups utilized for transmitting in opposite directions, that is, the 14,000 and 16,100 carriers are paired as the oppositely directed channels of one circuit, the 10,700 and 19,750 cycle channels of a second circuit, and the 7,700 and 23,400 cycle channels of a third circuit. With such an arrangement low frequency line L_1 would be associated through hybrid coil H_1 with transmitting channel TC_1 and receiving channel RC_2 , low frequency line L_2 through hybrid coil H_2 with transmitting channel TC_2 and receiving channel RC_1 , low frequency line L_3 through hybrid coil H_3 with transmitting channel TC_3 and receiving channel RC_3 . With such an arrangement, voice frequencies transmitted by transmitting band

120

125

130

filter TBF_1 in channel TC_1 and voice frequencies transmitted by transmitting band filter TBF_3 in transmitting channel TC_3 will combine in amplifier TA to produce 5 third order modulation products which will be transmitted to and fall within the range of the receiving band filter RBF_2 in receiving channel RC_2 and cause objectionable interference with message currents transmitted thereto over the line ML from its corresponding transmitting channel at the west end of the line. An example of this is the following:

The particular frequency having the 15 greatest amplitude in the side band transmitted by transmitting band filter TBF_1 is 1000 cycles below the carrier or 13,000 cycles. For purposes of illustration consider a frequency 2000 cycles below the carrier in the 20 side band transmitted by the band filter TBF_3 , or 5700 cycles. If we consider that channels TC_1 and TC_3 are transmitting messages simultaneously, then the side band frequency, 13,000 cycles, will combine in the 25 transmitting amplifier TA with the side band frequency, 5700 cycles, and form as one of the third order modulation products, $2s_1 - s_3$ or $2 \times 13,000 - 5700 = 20,300$ cycles. The particular third order modulation 30 product selected for illustration is the most objectionable. This frequency of 20,300 cycles is transmitted through low-pass grouping filter LGF and high-pass grouping filter HGF , is amplified by the receiving amplifier RA , and as it is within the transmission 35 range, 19,950-22,450 cycles, of receiving band filter RBF_2 in receiving channel RC_2 , it will be transmitted thereby and cause interference with the message currents received in that channel. As receiving channel RC_2 is paired with transmitting channel TC_2 and not with the transmitting channels TC_1 and TC_3 producing the objectionable third order modulation product, the intermodulation product will appear in receiving channel RC_2 as cross-talk. In other words, when two of the channels are being used for transmitting messages, there will be such objectionable cross-talk in the receiving apparatus connected with the third channel as to interfere with regular reception in that channel.

We will now consider the same example 55 in connection with the pairing of the channels in accordance with the invention, that is, where receiving channel RC_2 is paired with transmitting channel TC_1 , receiving channel RC_1 paired with transmitting channel TC_2 , and receiving channel RC_3 paired with transmitting channel TC_3 , as shown in the figure. As in the previous case the voice frequency of 13,000 cycles transmitted by transmitting band filter TBF_1 in transmitting channel TC_1 will combine in the transmitting amplifier TA with the voice fre-

quency of 5,700 cycles transmitted by transmitting band filter TBF_3 in transmitting channel and form as one of the third order modulation products, $2s_1 - s_3 = 20,300$ cycles, which will be transmitted through low-pass grouping filter LGF and high-pass grouping filter HGF , amplified by receiving amplifier RA , and fall within the range of the receiving band filter RBF_2 in receiving channel RC_2 . As receiving channel RC_2 in 75 this case is paired with transmitting channel TC_1 , instead of with transmitting channel TC_2 as in the previous arrangement, the intermodulation product 20,300 cycles will appear in receiving channel RC_2 as side tone 80 rather than as cross-talk. In other words with the arrangement of the invention, when two of the channels are being used for transmitting messages in one direction the frequency components due to intermodulation 85 of the voice frequencies transmitted by their respective transmitting band filters in the transmitting amplifier will only cause interference in the receiving apparatus paired with one of said channels, and will not interfere with the reception in the third channel.

The arrangement of the carrier channels in accordance with the invention has the additional advantage over other arrangements 90 in that the attenuation requirements of the low-pass filters which must be inserted between the receiving and transmitting circuits of each channel to prevent high frequency leakage are materially reduced. This 95 may be shown by the following numerical examples:

Suppose the channels are arranged as in the first case considered, that is, with receiving channel RC_1 paired with transmitting channel TC_1 , receiving channel RC_2 with transmitting channel TC_2 and receiving channel RC_3 with transmitting channel TC_3 , as in the usual manner. Then the carrier frequency 19,750 cycles associated with the demodulator DM_2 in receiving channel RC_2 will leak 100 through the hybrid coil H_2 into the modulator M_2 of transmitting channel TC_2 and combine therein with the carrier frequency 10,700 cycles, assigned to that channel to produce 110 the second order modulation products, $19,750 + 10,700 = 30,450$ cycles and $19,750 - 10,700 = 9,050$ cycles of which the 9,050 cycle component falls within the range, 8,000-10,500 cycles, of transmitting band filter 120 TBF_2 . In order to prevent this inter-modulation product from being objectionable, the low-pass filter F_2 inserted between the demodulator DM_2 and modulator M_2 must have large attenuation requirements.

Now, suppose the channels are arranged in accordance with the invention, that is, receiving channel RC_1 paired with transmitting channel TC_2 , receiving channel RC_2 paired with transmitting channel TC_1 , receiving channel RC_3 paired with transmitting channel TC_3 , 130

and receiving channel RC_3 paired with transmitting channel TC_3 , as shown in the figure, then the high frequency carrier 19,750 cycles associated with the modulator DM_2 in receiving channel RC_2 , will leak through hybrid coil H_1 into modulator M_1 of transmitting channel TC_1 and combine therein with the carrier frequency, 14,000 cycles, assigned to that channel to produce the second order modulation products, $19,750 - 14,000 = 5,750$ cycles and $19,750 + 14,000 = 33,750$ cycles, both of which are outside the range of transmitting band filter TFB_1 in that channel. Also the high frequency carrier 16,100 associated with the demodulator DM_1 in channel RC_1 will leak through hybrid coil H_2 into the modulator M_2 in transmitting channel TC_2 and combine with the high frequency carrier 10,700 cycles assigned to that channel to produce the second order modulation products $16,100 - 10,700 = 5,400$ cycles and $16,100 + 10,700 = 26,800$ cycles, neither of which are within the transmission range, 8,000-10,700, of transmitting band filter TFB_2 in that channel.

It is evident, then, that with the pairing of the channels as in the invention, that the attenuation requirements of the low-pass filters inserted between transmitting and receiving channels to attenuate high frequency leakage therebetween are much less than that required with other arrangements, thereby reducing the cost of such filters.

35 In the foregoing discussion reference has been made to certain definite frequencies for the purpose of giving concrete examples. It is to be understood, however, that the principles of the invention are independent of 40 the particular frequencies and frequency ranges hereinbefore referred to.

The invention has been described in connection with its application in a three-channel multiplex telephone system of the carrier suppression type, but it is to be understood that in accordance with the spirit of the invention as defined in the appended claims it is applicable as well to other types of multiplex carrier systems having any 50 number of channels.

What is claimed is:

1. In a multiplex carrier wave signaling system comprising a plurality of two-way carrier channels employing different carrier frequencies, all of the carrier frequencies in said channels used for transmission in one direction being comprised in a range below a certain limiting frequency, and all of the carrier frequencies in said channels used for transmission in the opposite direction being comprised in a range above said limiting frequency, the method of reducing near-end cross-talk which consists in selecting the particular carrier frequencies associated in each two-way channel for transmitting in opposite directions so that objectionable frequency components produced by intermodulation between the frequency bands transmitted in the same direction in any two of said channels will lie outside the range of the frequency bands transmitted in the opposite direction in any of the other channels.
2. In a multiplex carrier wave signaling system comprising a plurality of two-way channels distinguished from one another by the carrier frequencies they employ, the carrier frequencies being included in two separate groups, those used for transmission in one direction being all higher than a definite group-separation frequency, and those used for transmission in the opposite direction being all lower than said group-separation frequency, the method of reducing near-end cross-talk which consists in selecting the particular carrier frequencies to be paired in each of said two-way channels for transmission in opposite directions so that objectionable frequency components produced by intermodulation between the side band frequencies transmitted in the same direction in any two of said channels will fall within the range of the side band transmitted in the opposite direction in one of said channels and outside the range of the side bands transmitted in the opposite direction in the others of said two-way channels.
3. In a multiplex carrier signaling system, a plurality of two-way transmission channels, each of said channels utilizing a different carrier frequency for transmission, said carrier frequencies used for transmitting in one direction being all higher than a certain definite frequency, and those used for transmitting in the opposite direction all lower than said definite frequency, the one-way channels that are paired with the respective one-way channels throughout one directional group in order, being distributed throughout the other directional group in a different respective order such that the near-end interference between the channels will appear as side tone rather than cross-talk.
4. In a carrier signaling system, a plurality of one-way carrier channels, each employing a different carrier frequency, the carrier frequencies of all of said channels transmitting in one direction being below a definite limiting frequency, and the carrier frequencies of all of said channels transmitting in the opposite direction being above said limiting frequency, the one-way channels utilizing the lower group of frequencies being paired with the one-way channels utilizing the upper group of frequencies to form the opposite sides of two-way channels, the one-way channels that are paired with the respective one-way channels throughout one directional group in an order symmetrical with respect to said limiting frequency being arranged throughout the other direction.

tional group in a different respective order unsymmetrical with respect to said limiting frequency such that the objectionable modulation products produced by a combination 5 of frequencies in two of said channels will be received in one of said two channels rather than in a third channel.

5. In a multiplex carrier wave signaling system, a plurality of two-way transmission 10 channels, each employing a different carrier frequency, the carrier frequencies of the channels used for transmitting in one direction being comprised in an upper range, and the carrier frequencies used for transmitting 15 in the opposite direction being comprised in a lower range, the pairing of the oppositely directed carrier frequencies of the respective ranges to form the opposite sides of said two-way channels being such that 20 the uppermost carrier frequency of the lower range is paired with an intermediate carrier frequency of the upper range, and the lowermost frequency of the upper range is paired with an intermediate carrier frequency of 25 the lower range.

6. In a multiplex carrier wave signaling system, a plurality of two-way transmission channels, each utilizing a different carrier frequency, all of the said channels used for 30 transmitting in one direction employing carrier frequencies comprised in a range below a certain value, and all of said channels

used for transmitting in the opposite direction employing carrier frequencies comprised in a range above said value, the pairing of the oppositely directed carrier frequency waves in the different ranges to form the opposite sides of the two-way channels being such that the lowermost carrier frequency of the lower range is paired with the uppermost carrier frequency of the upper range, an intermediate carrier frequency of the lower range is paired with the lowermost carrier frequency of the upper range, and the uppermost frequency of the lower range is paired with an intermediate carrier frequency of the upper range.

7. In a multiplex carrier wave system employing waves of different frequency for the different simultaneous transmissions in which intermodulation components between channels transmitting in the same direction fall within the frequency range of certain of the oppositely directed channels, means permanently associating together as the two sides of a conversational circuit a said one of said certain channels in which the intermodulation components appear and one of the oppositely directed channels which give rise to said components.

In witness whereof, I hereunto subscribe my name this 12th day of December, A. D., 1925.

WAYNE B. NOTTINGHAM,
